UNITED STATES PATENT OFFICE

HAROLD F. DUNBAR, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA

MEANS FOR SUPPORTING CAR COUPLERS

Application filed March 5, 1929. Serial No. 344,408.

My invention relates to means for supporting car couplers in operative relation to the railway vehicles upon which they are mounted and is particularly concerned with preventing the sagging or drooping of the heads of couplers which reciprocate in draft and buffing.

The principal object of the invention is to provide a device which may be associated with the head of a car coupler so as to permit the coupler to be supported by a carrier which extends under the coupler head.

Car couplers generally in use at the present time, and notably the well-known standard D-15 coupler, are formed with large heavy heads, while the supporting carrier for the coupler is commonly located to the rear of the coupler head a sufficient distance to afford requisite clearance enabling the coupler to move rearwardly to a somewhat greater extent than the full normal travel of the draft gear with which the coupler is associated. As the coupler carrier when thus located to permit draft and buffing movements of the coupler supportingly cooperates with the latter at a point considerably to the rear of center of gravity to the coupler, the said coupler tends to sag or droop at the head end and as wear takes place in the means provided for attaching the coupler to the draft gear such drooping or sagging increases. This is detrimental to the proper operation of the coupler mechanism for, in order to provide for the proper operation of parts in the act of coupling and also to afford the requisite flexibility for vertical and horizontal angling when in service, couplers are formed with contours providing horizontal clearance between opposing couplers when the latter are in coupler relation, and if the

heads of the couplers droop the extent of such clearance is in effect diminished. To insure proper and efficient operation it is, therefore, important to maintain car couplers in horizontal position; and it is advantageous that this desirable result shall be accomplished in a simple and effective manner and by devices which may be associated with couplers of well-known form.

Generally stated, the principal feature of the invention consists in mounting a coupler

supporting member upon the under side of the head of a car coupler, and in providing a coupler carrier which extends under and forms a bearing for sustaining said supporting member, the coupler head and the said supporting member having overlapping portions or projections to prevent or limit horizontal shifting of the said supporting member with respect to the coupler, and means being provided for normally maintaining said supporting member in assembled relation to the coupler head.

Other features of the invention pertaining to advantageous structural forms and combinations will hereinafter appear and be particularly pointed out in the claims.

In the drawings showing a preferred form of the invention,—

Figure 1 is a view, partly in side elevation and partly in vertical section, of a mechanism embodying the invention, a portion of a striking casting of a railway car being shown associated therewith.

Figure 2 is an inverted plan view of the coupler head and the coupler supporting member associated therewith.

Figure 3 is a plan view of the coupler supporting member, portions of the coupler upon which it is mounted being shown in dot and dash lines to indicate the assembled relation of the parts.

Figure 4 is a detail sectional view on the line 4—4, Figure 3.

Figure 5 is a sectional view on the line 5—5, Figure 3.

Figure 6 is a sectional view of the coupler supporting member taken on the line 4—4, Figure 3 but looking in the direction of the arrows 6—6.

Figure 7 is a detail sectional view on the line 7—7, Figure 3.

In the drawings, 1 indicates the head of a car coupler and 2 the shank or stem thereof, while 3 is the coupler supporting member secured to the under side of the coupler head and 4 is the coupler carrier which extends under the supporting member 3 and upon which the latter slidably rests. While the coupler supporting means may be associated with a car coupler having a coupler head

whose under surface is provided with projections of any desired form, it is preferred to fashion the supporting block or member 3 so that it may be applied to car couplers which are at present in use and, therefore, a car coupler of the well known standard D-type has been illustrated in the drawings for the purpose of exemplifying the invention.

The under side of the coupler head is formed with stop portions or projections which cooperate with the supporting member 3 to prevent any substantial horizontal shifting of the latter with respect to the coupler. As shown, the projections on the under surface of the head of car couplers now in use may conveniently be, and preferably are, availed of as the projections for cooperating with the supporting block 3. In the type of coupler illustrated a portion 5 of the usual flange which borders the lock opening 6 in the lower wall of the coupler head vertically overlaps the adjacent side wall 7 of the supporting member 3 so as to function as a stop for preventing the supporting block from shifting toward the knuckle side of the coupler head. If desired, and as is preferred in order to afford a long and effective bearing, the side wall 7 may at its rear end also have overlapping engagement with the usual shoulder 8 with which the D-coupler is formed to the rear of the lock opening 6, the shoulder 8 being a continuation of the portion 5 of the flange bordering the lock opening, but being of somewhat less height than said flange.

The means provided on the coupler head for preventing the supporting member 3 from shifting laterally toward the guard arm side of the coupler, preferably are spaced transversely from the stop shoulders or projections 5 and 8 for a distance sufficient to insure stability of the member 3 against undue twisting with respect to the coupler head when the device is in service. Instead of providing special projections to constitute said means, the portion 9 of the depending flange at the forward end or face of the coupler, together with the boss 10 surrounding the pivot opening for the usual knuckle opener lever of the coupler, may be conveniently availed of to prevent lateral shifting of the block 3 toward the guard arm side of the coupler head. For overlapping the stop projection 9 so as to cooperate therewith, the supporting member 3 is preferably provided with an arm 11 which extends forwardly from the adjacent side wall 12 of said supporting member; and for overlappingly engaging the side of the boss 10 the supporting member 3 is formed with a face or shoulder 13 corresponding in curvature to the exterior of said boss. Forward movement of the coupler supporting member 3 with respect to the coupler head is limited by the engagement of the forward face of the transversely extending bar 14 of the member 3 with the transversely extending shoulder

15 on the under side of the coupler head; while rearward movement of the block 3 with respect to the coupler is prevented by providing said block with a lug 16 which extends inwardly so as to overlap the forward face 70 of the boss 10. In addition to preventing forward shifting of the supporting means with respect to the coupler head, the transverse bar 14 also serves as a tie for connecting the side walls 7 and 12 of the block 3 at their 75 rear upper corners. The side walls of the member 3 are also rigidly connected at their lower ends by a horizontally extending web 17 which forms a bearing plate for cooperating with the upper surface of the wear shoe 80 18 with which the coupler carrier 4 is preferably provided. To minimize the width of the coupler carrier longitudinally of the car, while at the same time insuring that the coupler supporting member 3 shall amply 85 overlap the carrier 4 in all positions of draft and buffing the coupler may occupy, the bottom plate or bearing member 17 of the block 3 preferably projects rearwardly somewhat 90 beyond the coupler head and extends forwardly into overlapping relation with the lock opening 6 in the coupler head, the said plate 17 being suitably recessed, as indicated at 19, so as to provide clearance for the coupler lock and its actuating mechanism. 95

The supporting member or block 3 is preferably maintained in proper assembled relation to the coupler head 1 by means of a bolt 20 which passes through a perforated lug 21 with which the block 3 is provided on the 100 side toward the coupler knuckle and through an opening 22 formed in the lower wall of the coupler head adjacent the knuckle side thereof. This bolt, which is so positioned that it does not interfere with any of the 105 movable elements of the car coupler, prevents vertical movement of the coupler supporting block 3 with respect to the coupler head and thus, in conjunction with the interlocking projections with which said lock and head 110 are provided, insures the maintenance of the block in correct operating position.

I claim:

1. The combination with a car coupler having a head provided on its lower side with a lock opening, of means for supporting the same comprising a member removably connected to the coupler head and positioned beneath the latter and movable therewith, a coupler carrier extending under and supportingly engaging said coupler supporting member, and a bolt for connecting said supporting member to the coupler head, said head and said supporting member each being provided with an aperature for receiving said bolt and having cooperating portions on opposite sides of said lock opening for preventing said supporting member from shifting horizontally with respect to the coupler head, and said coupler supporting member 130

being formed with a horizontally extending bottom plate overlapping opposite sides of said lock opening and slidably engaging said coupler carrier.

wall vertically overlapping said flange and being provided with a portion overlapping said projection transversely of the coupler.

In testimony whereof I affix my signature.

HAROLD F. DUNBAR. 70

- 5 2. The combination with a car coupler, of
means for supporting the same comprising a
member removably connected to the coupler
head and positioned beneath the latter and
movable therewith, and a coupler carrier ex-
10 tending under and supporting said coupler
supporting member, said coupler head being
provided on its lower side with a lock open-
ing, and said coupler supporting member
being formed at its lower end with a bottom
15 plate which extends rearwardly of said lock
opening and overlaps opposite sides of said
opening.

3. The combination with a car coupler, of
means for supporting the same comprising a
coupler supporting member removably con-
nected to the coupler head and positioned be-
neath the latter and movable therewith, and
a coupler carrier mounted on the car and ex-
tending under and engaging said coupler sup-
porting member, said supporting member be-
ing provided with laterally spaced side walls
and having a bottom bearing plate connecting
said side walls, said bottom plate being re-
cessed to afford clearance for coupler locking
means.

- means.

4. The combination with a car coupler, of means for supporting the same comprising a coupler supporting member detachably connected to the coupler head and positioned beneath the latter and movable therewith, and a coupler carrier rigidly mounted on the railway vehicle with which said coupler is associated, said carrier extending under and supportingly engaging the coupler supporting member, the head of said coupler being provided at its forward end on its under side with a depending flange portion and having a lock opening and a depending flange portion adjacent said lock opening, and said coupler supporting member being provided with a forwardly extending arm adapted to cooperate with said first-named flange portion and having a portion adapted to cooperate with the said flange portion adjacent said lock opening.

5. The combination with a car coupler, of
means for supporting the same comprising a
coupler supporting member detachably con-
nected to the coupler head and positioned be-
55 beneath the latter and movable therewith, and
a coupler carrier extending under and sup-
portingly engaging said supporting member,
the underside of the head of said coupler be-
ing provided with a lock opening and having
60 a flange adjacent thereto and also being pro-
vided with a downwardly extending projec-
tion adjacent the opposite side of said open-
ing, and said coupler supporting member be-
ing provided with a bottom plate slidably
65 supported by said carrier and having a side
